UNITED STATES PATENT OFFICE.

HENRY J. WIEGAND, OF MILWAUKEE, WISCONSIN, ASSIGNOR TO THE CUTLER-HAMMER MFG. CO., OF MILWAUKEE, WISCONSIN, A CORPORATION OF WISCONSIN.

HAND-WHEEL.

1,174,215.

Specification of Letters Patent.

Patented Mar. 7, 1916.

Application filed October 8, 1908. Serial No. 456,802.

To all whom it may concern:

Be it known that I, HENRY J. WIEGAND, a citizen of the United States, residing at Milwaukee, in the county of Milwaukee and State of Wisconsin, have invented new and useful Improvements in Hand-Wheels, of which the following is a full, clear, concise, and exact description, reference being had to the accompanying drawing, forming a part of this specification.

My invention relates to improvements in hand wheels, and has for its object to improve the construction of the hand wheel disclosed in my former Patent, No. 821,272, dated May 22, 1906.

One feature of my present invention resides in the construction of a rim which is formed of sheet-metal, but has the appearance and all of the advantages of a solid rim, it being substantially circular in cross-section.

Another feature of my invention resides in the construction of the spider which increases the strength and durability of the wheel and also gives the same a more finished appearance.

For the purpose of more fully disclosing my invention, I have illustrated the preferred embodiment thereof in the accompanying drawing. The several views in the drawing are as follows:

Figure 1 is a bottom plan view of the wheel. Fig. 2 is a sectional view taken on line 2—2, Fig. 1, and Figs. 3 and 4 are detail views.

The hand wheel illustrated is formed entirely of sheet metal, with the exception of the hub. The rim is preferably formed in two parts, an upper member 1 and a lower member 2. The members 1 and 2 comprise stamped circular plates or rings so bent transversely as to form a rim substantially circular in cross-section when the same are fitted together as illustrated. In practice

I prefer to make the upper member of wider material than the lower member, so that when the same is bent transversely, as illustrated, the curve of its cross-section is greater than a semi-circle. This renders the rim of greater strength than by forming the two members alike. Furthermore, by forming the upper member as described, the edges of both members are hidden when the rim is viewed from the top. Owing to the fact that the two members are curved

substantially concentrically, they may be placed together, edge to edge, on the outside to form a substantially smooth and continuous surface without the necessity of any special preparation of their edges. In practice I prefer to have the inner edge of the upper member overlap the inner edge of the lower member, inasmuch as the appearance of the wheel is not marred thereby, and this arrangement permits the parts to be more easily assembled. The two members are held together in the manner hereinafter described. The rim is mounted on a spider, which preferably comprises three arms 3 radiating from a substantially circular central portion 4. The arms 3 are preferably formed integrally with the portion 4, the entire spider being stamped from sheet-metal. For the purpose of strengthening the arms and giving the same the appearance of being solid, the same are curved transversely, their edges being hidden when the wheel is viewed from the top. The extremities of the arms 3 are flat and are secured to the inside of the upper member of the rim, preferably by means of rivets 5. The lower member of the rim has notches stamped therein to permit the insertion of the ends of the arms 3 in the upper member of the rim and to form tongues 6. The tongues 6 are bent downwardly to engage the under side of the arms 3 and are secured thereto, preferably by solder. It will thus be seen that the two members of the rim are held together by securing both of the same to the arms 3. The central portion 4 of the spider is secured by rivets 7 to the annular flange 8 of a hub 9. The hub is preferably formed of cast-metal and provided with a socket or recess 10 for the reception of a shaft. A screw 11 threaded into the side of the hub provides means whereby the same may be locked to the shaft.

In order to strengthen the spider and relieve the strain on the rivets 7, when the wheel is in use, I provide the central portion 4 with downwardly extending flanges 12, adapted to fit tightly around the flange 8 on the hub. The provision of the flanges 12 adds greatly to the strength of the wheel. Projecting outwardly from one of the flanges 12 is a pointer 13, preferably stamped integrally therewith.

It will thus be seen that a hand-wheel constructed in accordance with my inven-

tion, has the same appearance and all of the advantages of a solid wheel, while the same may be produced at a much smaller cost.

5. Of course, my invention is not limited to the specific construction illustrated, and various modifications may be made therein without departing from the spirit thereof.

Having thus described my invention, what 10 I claim as new and desire to secure by Letters Patent, is:

1. A hand wheel comprising a spider having radial arms and a hand rim secured to the extremities of said arms and having a 15 gripping space between each adjacent pair of said arms, said rim comprising a plurality of transversely curved metallic rings rigidly secured to the arms of said spider to form a ring substantially circular in cross section.

2. In a hand wheel, the combination with a spider having radial arms, of a hand rim formed of transversely curved sheet metal rings rigidly secured to the arms of said 25 spider to form a ring substantially circular in cross section, the ends of said arms being concealed within said rim.

3. In a hand wheel, the combination with a spider having radial arms, of a hand rim 30 formed of a pair of transversely curved sheet metal rings rigidly secured to the arms of said spider to form a ring substantially circular in cross section, the outer edges of said rings being flush and the inner edges thereof 35 being overlapped.

4. In a hand wheel, the combination with a spider having radial arms, of a hollow hand rim substantially circular in cross-section and formed of a pair of sheet-metal 40 rings, one of said rings being recessed to receive the ends of said arms and having tongues secured to the underside thereof, said arms being secured to the inside of the other of said rings.

45. 5. In a hand wheel, the combination with a spider having radial arms, of a hollow hand rim substantially circular in cross-section and formed of a pair of sheet-metal

rings, the inner edges of said rings overlapping, and the outer edges thereof being flush, 50 one of said rings having apertures for receiving the ends of said arms and having tongues secured to said arms, said arms being secured to the inside of the other of said rings.

55. 6. In a hand wheel, the combination with a sheet-metal spider having radial arms curved transversely, of a hollow hand rim substantially circular in cross-section and formed of a pair of sheet-metal rings, said 60 rim having apertures formed therein for receiving the ends of said arms.

7. In a hand wheel, the combination with a sheet-metal spider having radial arms curved transversely, of a hollow hand rim 65 substantially circular in cross-section and formed of a pair of sheet-metal rings, one of said rings having apertures formed therein for receiving the ends of said arms and having tongues formed thereon and secured 70 to said arms, the other of said rings being riveted to said arms.

8. A hand wheel having a spider formed of sheet metal and provided with arms radiating from the central portion thereof and 75 a hub secured to the central portion of said spider, said central portion having its edges between said arms bent to form flanges to engage the sides of said hub.

9. A hand wheel having a spider formed 80 of sheet metal and provided with arms radiating from the central portion thereof, said arms being curved transversely and said central portion having its edges bent to form angularly disposed flanges continuous with 85 said arms, and a hub secured to the central portion of said spider between the flanges thereof.

In witness whereof, I have hereunto subscribed my name in the presence of two 90 witnesses.

HENRY J. WIEGAND.
